APPARATUS FOR MAKING WIRE FABRIC SEAMS

Paul J. Abendroth and Otto A. Abendroth,
Appleton, and Walter Wessenberg, Menasha,
Wis.

Application October 1, 1934, Serial No. 746,406

3 Claims. (Cl. 140—3)

This invention pertains to wire cloths or fabrics of the type commonly used in making paper on Fourdrinier machines, and more particularly to a novel apparatus for joining the ends of the fabric together to form the desired endless construction.

Difficulty has not only been experienced in producing a seam which would be mechanically strong, (as explained in the co-pending application of Otto A. Abendroth, Serial No. 746,407), but great difficulty has also been experienced in the actual process of joining the ends of the fabric together to form the seam. The Fourdrinier wires are of extremely fine mesh, and hence the individual wires are almost invisible to a naked eye. A great length of time is required to drill a workman (generally a year) before sufficient skill is obtained by him to accurately solder, braze, or weld the ends of the fabric together.

One difficulty is in holding the fabric ends; another is that the heat developed tends to burn the fabric, and thus the wires will often break at a point spaced from the seam; and still another difficulty is the guiding of the flame along the seam.

It is therefore one of the salient objects of our present invention to provide an improved apparatus for effectively holding the ends of the Fourdrinier wires in correct relation against movement, and to only expose the ends of the individual wires, which are to be joined, to view, to protect the body of the fabric against the flame.

A further object of our invention is to provide a novel apparatus for holding the ends of the Fourdrinier wires, whereby the workman will be guided in his work so that he will be enabled to quickly and accurately apply the solder to the wire ends, and apply correctly the flame to the joint.

A further object of our invention is the provision of novel holding plates, which are formed of a relatively great thickness and width, the plates completely covering the body of the fabric adjacent to the joint, and only exposing to view the individual wires which are to be joined, the plates being formed of aluminum, whereby heat developed by the flame will be readily absorbed and dissipated by the plates, so that the body of the fabric will not be burned or scorched.

A further object of our invention is to provide a novel means for joining the ends of Fourdrinier wires together, which consist in first clamping the ends of the fabric together to expose to view only the individual wire ends which are to be joined; second, rolling down of the ends, whereby the

same will lie in substantially parallel relation; third, applying liquid solder to the exposed ends; and, finally, applying the desired degree of heat to the solder and exposed wire ends.

A still further object of our invention is to provide an improved apparatus for connecting the ends of the Fourdrinier wires together, whereby the operator's work will be simplified, and whereby the formation of the desired joint is assured.

With these and other objects in view, the invention consists in the novel construction, arrangement, and formation of parts, as will be hereinafter more specifically described, claimed, and illustrated in the accompanying drawing, in which drawing:

Figure 1 is a top plan view of our improved apparatus, the mesh of the Fourdrinier wire being shown exaggerated.

Figure 2 is a fragmentary transverse sectional view through our improved apparatus, showing the Fourdrinier wires clamped in place and ready for the second step of rolling the wire ends flat, the meshes of the wires being shown exaggerated.

Figure 3 is an enlarged fragmentary top plan view to more clearly illustrate the overlapping of the wire ends.

Figure 4 is a fragmentary detail front elevation of the roller utilized to straighten out the warp wires of the Fourdrinier fabric.

Referring to the drawing in detail, wherein similar reference characters designate corresponding parts throughout several views, the letter A generally indicates our improved apparatus. One of the salient features of our invention is the use of the pairs of clamps 5 and 6 which are utilized to grip the ends of the Fourdrinier wires. The clamp 5 includes a rigid body plate 7 and a removable top plate 8. The clamp 6 embodies like plates, and thus includes a rigid bottom plate 9 and a removable top plate 10. As explained above, the bottom plates 7 and 9 of the clamps 5 and 6 are rigidly held in place against movement, and these plates can be firmly connected in any desired manner with a supporting frame 11, which can be in the nature of a table. Only a fragment of this frame has been shown, as any character of frame can be utilized. It is preferred, however, to mount this frame on wheels, whereby the same can be slid transversely under the fabric. In the present instance we have shown the bottom plates 7 and 8 spaced from the top of the frame by means of spacing strips 12. The outer faces of the plates 7, 8, 9, and 10, at their inner longitudinal edges, are bevelled, as at 13, to form a substantially knife edge 14. This

bevel can be on a forty-five degree angle if so desired.

The top plates 8 and 10 can be detachably secured to the bottom plates 7 and 9 in any desired manner, such as by the use of clamps. In the present instance we have shown the top plates 8 and 10 connected to the bottom plates 7 and 9 by bolts 15, which are located adjacent to the ends of the plates and beyond the Fourdrinier wires. In actual practice, the plates are about fifteen feet long or longer so as to accommodate the greatest width of Fourdrinier wires. The plates are formed relatively thick, and relatively wide, so that a substantial part of the body portion of the fabric on each side of the seam will be covered. The plates can be approximately six inches wide, and this not only forms a broad clamp for engaging the fabric, but also protects the fabric from heat, as will be later brought out.

20 The lower plates 7 and 9 have their adjacent edges connected together at spaced points by bridge straps 16. These bridge straps directly below the space between the plates are provided with U-shaped bite portions 17, which slidably and detachably support the wire-supporting bar 18, which can be formed from any desired metal, such as steel.

In connection with the novel clamps 5 and 6, we employ a roller 20 for straightening out the ends of the warp wires of the fabric incidental to the connecting of these wires together, as will also be more clearly described. The roller is rotatably supported by suitable bearing wires 22, which can be carried by a manipulating handle (not shown). The roller includes a central flat peripheral portion 23, the width of which is equal to the distance between the clamps 5 and 6. On opposite sides of the flat central peripheral portion 23 the roller is bevelled, as at 24, and this bevelled portion conforms substantially to the bevel 13 of the clamps 5 and 6.

The ends of the Fourdrinier wire or fabric W is indicated by the reference numbers 25 and 26 in the drawing, and by referring to Figures 1 and 2 it will be noted that these ends are firmly clamped between the plates 7 and 8, and 9 and 10. In actual practice, the Fourdrinier wire W is supported in the usual apparatus, and the top plates 8 and 10 of the clamps 5 and 6 are removed. The frame 11 is then slipped under the Fourdrinier wire, and the ends 25 and 26 are placed on top of the plates 7 and 9 with the warp ends 27 protruding beyond the inner longitudinal edges of the plates. The top plates 8 and 10 are then placed 55 upon the ends 25 and 26 of the Fourdrinier wire and firmly secured in place by the screws 15. This effectively holds the ends 25 and 26 in place, and the warp ends 27 are only exposed to view. In accordance with our method, the end shot or weft wires of the fabric ends 25 and 26 are removed prior to the clamping in place of the Fourdrinier wire W. This permits effective overlapping of the warp wires 27 and the forming of a smooth seam without undue bulk. The supporting rod 18 can now be slid in the guide 17 of the bracket 16, under the warp ends 27, after

which the roller 20 is placed in the space between the clamps, and is rolled back and forth over the warp ends 27, so as to straighten these ends and thus bring about the formation of the smooth joint. After the warp wires are straightened, the 5 bar or rod 18 is removed.

A liquid silver soldering compound is now used, and this is preferably applied by means of a fine camel's hair brush. After the application of the solder, a torch is brought into play and is moved 10 back and forth along the space between the clamps. This effectively solders the ends of the wires, and after the soldering operation the top plates 8 and 10 can be removed and the frame slipped transversely from under the Fourdrinier 15 wire W.

We lay particular stress on the clamps 5 and 6, and the material from which the plates of the clamps are made.

As heretofore explained, in the use of a torch, 20 the Fourdrinier wires are often burnt on opposite sides of the seam, and the wires will break at the burnt portions. While the use of our plates 7, 8, 9, and 10 will eliminate this condition to a large extent, it is necessary to form the 25 plates from some material that will absorb the heat and dissipate the same to the atmosphere. After careful experiments, we have found that aluminum is the ideal metal from which to form the plates, as this metal will quickly absorb and 30 dissipate the heat to the atmosphere. While we have specified aluminum, it is to be understood that we can use "duro" aluminum, or any aluminum alloy or metal that oxidizes rapidly and 35 will not solder.

Changes in details may be made, but what we claim as new is:—

1. An apparatus for joining the ends of fabric wires together, comprising a pair of spaced clamps, each including a rigid bottom plate and a removable top plate, and removable means for supporting the free wire ends between the plates. 40

2. An apparatus for joining the ends of wire fabric together, comprising a pair of spaced clamps, each including rigid bottom plates and removable top plates, a removable bar disposed between the clamps for initially supporting the free wire ends between the clamps, and a roller for straightening out the wire ends on top of the bar movable between the clamps. 50

3. An apparatus for joining the ends of wire fabric together, comprising a pair of spaced clamps, each including rigid bottom plates and removable top plates, a solid bar disposed between the adjacent edges of the bottom plates for firmly supporting the free ends of the longitudinal wires of the fabric between the clamps, and a roller for straightening out said free wire ends on top of the bar movable between the clamps, said roller having a central annular bearing face and bevelled edges for conforming to the configuration of the adjacent edges of the top plates. 55
